UNITED STATES PATENT OFFICE.

FREDERICK WARD AND SYDNEY ASLINE WARD, OF SHEFFIELD, COUNTY OF YORK, ENGLAND.

HORSESHOE.

SPECIFICATION forming part of Letters Patent No. 363,925, dated May 31, 1887.

Application filed January 25, 1887. Serial No. 225,496. (No model.) Patented in England October 15, 1886, No. 13,146.

To all whom it may concern:

Be it known that we, FREDERICK WARD and SYDNEY ASLINE WARD, subjects of the Queen of Great Britain, residing at Sheffield, in the county of York, England, have invented certain new and useful Improvements in the Construction of Calks for Horseshoes and Means for Attaching Same, (patented in Great Britain by Letters Patent No. 13,146, dated October 15, 1886;) and we do hereby declare that the following is a full, clear, and exact description thereof, reference being had to the accompanying drawings, which form a part of this specification.

15 This our invention relates to the construction of sharpening bits or calks, such as are attached to horseshoes to prevent slipping, and to the means for attaching them to the shoes without the use of screws, pins, or other loose 20 appliances.

It consists in making the sharpening-bits (either by the process of rolling or by stamping, or other similar means) of a V shape in cross-section, and fitting them into corresponding 25 undercut grooves formed in the shoe.

The annexed sheet of drawings illustrates our invention.

Similar letters of reference indicate similar parts in all the figures.

30 Figure 1 represents in two views one of our sharpening-bits; Fig. 2, a modification of same; Fig. 3, a perspective view of a horseshoe with one of the bits in position.

In carrying out our invention we roll, stamp, 35 forge, or otherwise shape or produce the V-shaped bits; but preferably we produce the material in lengths by rolling, and we saw or otherwise cut it up to the desired lengths, as shown in Fig. 1.

40 As it is necessary the material should be hard to resist wear, and elastic to enable it to be compressed, we find that steel is the most suitable material, so that the bits may be hardened and tempered; or, if the steel is made of 45 a sufficiently hard nature, these processes may be dispensed with and the steel be left in its original state.

In carrying our invention into practice a suitable number of grooves—such as D in Fig.

3—are formed on the under side of the shoe. 50 They may be made both at the toe and the heel of the shoe or only at the heel, as shown in Fig. 3 of the drawings. These grooves are made rather narrower than the measurement of the base of the bit formed by the sides B B, 55 so that when the said bits are driven into the said grooves, which is readily accomplished by means of a hammer, the two sides are of necessity compressed toward each other, and when in the desired position the bits are held 60 securely by the reacting force and frictional contact of the elastic compressed sides B B against the sides and bottom of the groove D, no further fastening appliances being necessary. 65

Although we have hitherto described these improved sharpening-bits only in connection with shoes, it is obvious that they may be similarly applied to attachments to shoes or to overshoes. 70

A modified form of the sharpening-bit is shown in Fig. 2, in which the edges of the sides B are slightly turned back, as shown. The grooves D are made to correspond. One or more slots, E, may be cut in the sides B, if 75 desired.

It will be observed that with either form of our calks but one holding groove or seat is required for each calk, and that the head of each calk, as well as the base of each, is hollow, as 80 seen in Fig. 3. This construction adapts the calks to be made self-fastening, as aforesaid, and also renders them to a certain extent vertically elastic when the weight of the horse is upon them, while any permanent spread increases the tightness with which they are held 85 in place.

Having thus described our invention and the manner of carrying it into practice, we wish it to be understood that we do not claim 90 the use of undercut grooves formed in horseshoes, nor the use of solid fasteners or calks fitted therein; but

What we desire to secure by Letters Patent is— 95

In combination with a horseshoe or the like provided with a single undercut groove for each calk, the within-described hard-metal

elastic calks or sharpening-bits constructed of **V** shape in cross-section, the head or protruding portion, as well as the base of each, being hollow, whereby they are adapted to be compressed in driving them into said grooves and securely self-fastened by expansion, substantially as hereinbefore specified.

In testimony that we claim the foregoing as

our own we have affixed hereto our signatures in presence of two witnesses.

FREDK. WARD.

SYDNEY ASLINE WARD.
